DESIGN FOR A BLOUSE

William Freedman, New York, N. Y.

Application December 31, 1936, Serial No. 66,827

Term of patent 3½ years

To all whom it may concern:

Be it known that I, William Freedman, a citizen of the United States of America, residing in Manhattan, county of New York, and State of New York, have invented a new, original, and ornamental Design for a Blouse, of which the following is a specification, reference being had to the accompanying drawing, forming part thereof, wherein,

Figure 1 is a front view of a blouse, showing my new design.

Figure 2 is a rear view of the blouse, shown in Figure 1.

The characteristic feature of my design resides in the combination on the blouse as shown of ruche trimmed panels extending from the side, sleeve, and collar seams, giving a bolero appearance to the blouse.

I claim:

The ornamental design for a blouse, substantially as shown and described.

WILLIAM FREEDMAN.
